DESIGN FOR AN UMBRELLA-STAND

James F. Sykes, Pittsburgh, Pa.

Application February 24, 1934, Serial No. 50,856

Term of patent 7 years

To all whom it may concern:

Be it known that I, JAMES F. SYKES, a citizen of the United States, residing at Pittsburgh, in the county of Allegheny and State of Pennsylvania, have invented a new, original, and ornamental Design for Umbrella-Stands, of which the following is a specification, reference being had to the accompanying drawing, forming part thereof.

Fig. 1 is a front elevation of the umbrella-stand showing my new design.

Fig. 2 is a side elevation of the umbrella-stand, and

Fig. 3 is a top plan-view thereof.

The umbrella shown in dot and dash lines in Figs. 1 and 2 is not a part of the design claimed.

I claim:

The ornamental design for an umbrella-stand, as shown and described.

JAMES F. SYKES.
